tion of Tennessee

Application January 7, 1941, Serial No. 373,498

4 Claims. (CL 217—65)

The present invention relates to crates and particularly to crates of the type generally used in the transportation of milk bottles. Objects of the invention are to provide a crate of strong yet economical construction and one wherein the bottles are safeguarded from breakage due to rough handling. The features of improvement whereby these objects are obtained will be described with reference to the embodiment shown, by way of example, in the accompanying drawing.

In the drawing:

Figure 1 is a plan view partly broken away of a crate constructed in accordance with the invention.

Figure 2 is a section substantially on line 2—2 of Figure 1.

Figure 3 is an isometric view showing the bottom construction in part and an associated corner element.

Figure 4 is a section on line 4—4 of Figure 3, and

Figure 5 is a bottom plan view of the corner element of Figure 3.

Referring to the drawing, reference numeral 10 designates a rectangular continuous bottom wire or rod which constitutes a runner, the rod being here contemplated as of oblong form with rounded corners. Rising from each corner of the wire is an element 11 which includes an outer angle 12 conformed to the outside of a corner of wire 10 and welded thereto, the angle lapping the wire so that its lower edge is substantially at the bottom of the wire but no lower. Element 11 includes an inner angle 15 having its lower end centrally split longitudinally and bent outwardly rectangularly to provide feet 16 and 17 which are welded to the top of the wire 10 at the corner so that the walls of the angle are substantially parallel to the walls of angle 12. A stacking iron 18 is secured to the upper end of angle 15.

A supporting grid includes crossed wires 19 and 20 which are welded together and whose ends are welded on top of the opposite sides and ends of the bottom wires. Slats 21 extend above the sides and ends of the bottom wire 10 and have their ends received between the inner and outer angles of the corner elements, lower right of Figure 1, and riveted thereto, the spacing of the inner and outer angles as determined by the feet 16 and 17 being the thickness of the slats. Just inwardly of the slats the grid wires are bent abruptly upwardly as at 22 and 23 to provide horizontal supporting portions elevated substantially above the secured ends of the grid wires.

Positioning grids 24 and 25 are supported in kerfs of the slats above the supporting grid.

The described arrangement affords a particu-

larly light and rigid bottom and corner unit and one of particular durability in view of the welding of all joints. The upward offsetting of the wires of the supporting grid permits the latter to yield freely without striking the ground or floor in a manner which might cause breakage of the contained bottles if the crate is dropped. Desirably the offsetting is such that the grid wires will not catch on the stacking irons when one crate is being slid on another during stacking.

The invention is, of course, susceptible of variation in detail from the specific disclosure herein, and, consequently, we do not limit ourselves in such matters except as in the following claims.

15. We claim:

1. A crate having a rectangular bottom wire constituting a runner, corner elements rising from said wire, each of said elements including an outer angle welded to the outside of the wire and an inner angle having a foot portion welded to the top of the wire, a supporting grid welded to said wire, and slats above said wire with their ends secured between the angles of said corner elements.

2. A crate having a rectangular bottom wire constituting a runner, corner elements rising from said wire, each of said elements including an outer angle welded to the outside of the wire and an inner angle, the bottom portion of said inner angle being split and bent outwardly to provide feet welded on top of the wire, a supporting grid welded to said wire, and slats above said wire with their ends secured between the angles of said corner elements.

3. A crate having a rectangular bottom wire constituting a runner, corner elements each including inner and outer angles rising from said wire and welded thereto, one of the angles of each of said elements being bent at the top of the wire to provide a spacing from its associated angle greater than the diameter of said wire, and slats above said wire secured between the angles of said corner elements.

4. A crate having a rectangular bottom wire 45 constituting a runner, metal corner elements each including inner and outer angles rising from said wire, the angles of each corner element having parallel portions spaced from each other a distance greater than the diameter of said wire, spacing means between the angles of each corner element welded to said wire, one of the angles of each corner element being welded directly to said wire and the other being fixed to said wire through said spacing means, a supporting grid welded to said wire, and slats above said wire secured between the angles of said corner elements.

5. A crate having a rectangular bottom wire 50 constituting a runner, metal corner elements each including inner and outer angles rising from said wire, the angles of each corner element having parallel portions spaced from each other a distance greater than the diameter of said wire, spacing means between the angles of each corner element welded to said wire, one of the angles of each corner element being welded directly to said wire and the other being fixed to said wire through said spacing means, a supporting grid welded to said wire, and slats above said wire secured between the angles of said corner elements.

DONALD R. SWINGLE.
WILLIAM W. ROBINSON.
